UNITED STATES PATENT OFFICE.

WILLIAM THOMSON, OF CAMBERWELL, LONDON, AND ARTHUR THOMAS HOWSON, OF DEPTFORD, LONDON, ENGLAND.

MEANS FOR OPENING ENVELOPS.

1,198,679.

Specification of Letters Patent. Patented Sept. 19, 1916.

Application filed November 23, 1915. Serial No. 63,078.

To all whom it may concern:

Be it known that we, WILLIAM THOMSON and ARTHUR THOMAS HOWSON, both subjects of the King of Great Britain, and residing, respectively, at 66^A Peckham road, Camberwell, London, England, and 35 High street, Deptford, London, England, have invented new and useful Improvements in Means for Opening Envelops, of which the following is a specification.

Our invention relates to envelops for postal and other purposes and to that class of such envelop designed to have inserted into it a card or the like provided with inclined edges so arranged that the act of withdrawing the said card from the closed envelop opens the latter. Envelops of this class as heretofore constructed are provided with a slit or opening in the edge through which a portion of the card projects, to allow of the said card being grasped by the fingers for opening or cutting the edge of the envelop. This projecting portion is objectionable in that it constitutes an obstruction which interferes with the sorting of letters, and is liable to be torn off in transit; furthermore, the formation of a slit in the edge of an envelop is detrimental in that the envelop is more liable to tear than when the edge is intact.

According to our invention we obviate these objections by making the slit in the face of the envelop, the said slit being preferably semi-circular so as to form a kind of flap and having its extremities terminating at some little distance from the envelop edge, and by providing the cutter card with a tab that shall lie substantially flat on the said flap, and be prevented from projecting beyond the edge of the envelop, by the portions of the cutting edges of the card, adjacent to the tab, engaging those portions of the envelop, between which the slit extends.

Our invention will be readily understood by reference to the accompanying drawing, in which:—

Figure 1 is a front view of an envelop provided with an opening device arranged according to the said invention, and Fig. 2 is a section on the line 2—2, Fig. 1. Fig. 3 is a view of the envelop without the opener, and Fig. 4 is a view of the opener.

a indicates an envelop which is of ordinary construction except that on the front

face a slit b, which as shown is semi-circular, is formed which terminates at c, c at some distance from the edge of the envelop and which forms the flap d.

e indicates the opener or cutter card which is designed to approximately fit the said envelop and is provided with a tab f of a width adapted to pass through the slit b and is prevented from projecting beyond the edge of the envelop, by the upper portions e' of the cutting edges e² of the card engaging those portions c of the envelop between which the slit extends, as shown in Fig. 1.

The flap d which is formed by the semi-circular slit b and which lies behind the tab f serves as a guard between the cutter card e and the letter or other contents g of the envelop, so that when the said tab is grasped to open the envelop there will be no liability of grasping such letter or the like.

It will be obvious that when withdrawing the cutter card e the latter will first sever the front of the envelop between the extremities c of the slit b and the envelop edge and then cut along the edge of the latter in the usual manner. After the envelop has been opened, the semi-circle opening formed by the cutting out of the flap allows of the contents being easily withdrawn between finger and thumb.

Although our improvements are primarily intended for envelops for postal purposes it is obvious that such envelops may be used for other purposes. It is also to be understood that our invention can be applied to envelops having a tuck flap such as is used for penny postage.

Claims:

1. The combination with an envelop provided in one of its faces with a slit which is spaced away from the edge of the envelop, of a cutter card located within said envelop and provided with a tab which projects through said slit and is prevented from projecting beyond the edge of the envelop by the portions of the cutting edges of the card adjacent to the tab engaging those portions of the envelop between which the slit extends.

2. The combination with an envelop provided in one of its faces with a slit which is spaced away from the edge of the envelop and forms a tongue in the face of the same, of a cutter card located within said envelop

and provided with a tab which projects through said slit and is prevented from projecting beyond the edge of the envelop by the portions of the cutting edges of the 5 card, adjacent to the tab, engaging those portions of the envelop between which the slit extends, said tongue forming a guard between the tab and the contents of the envelop to prevent the engagement of the tab 10 with the inclosure.

3. The combination with an envelop provided in one of its faces with a semi-circular slit which is spaced away from the edge of the envelop and forms a tongue in the 15 face of the same, of a cutter card located

within said envelop and provided with a tab which projects through said slit and is prevented from extending beyond the edge of the envelop by the portions of the cutting edges of the card, adjacent to the tab, 20 engaging those portions of the envelop between which the slit extends, said tongue forming a guard between the tab and the inclosure to prevent the engagement of the tab with the same.

WILLIAM THOMSON.
ARTHUR THOMAS HOWSON.
